UNITED STATES PATENT OFFICE.

THOMAS WHITNEY, OF CHICAGO, ILLINOIS.

DESIGN FOR A TOY.

SPECIFICATION forming part of Design No. 20,706, dated April 28, 1891.

Application filed February 24, 1891. Serial No. 382,633. Term of patent 3½ years.

To all whom it may concern:

Be it known that I, THOMAS WHITNEY, a citizen of the United States, residing at Chicago, in the county of Cook and State of Illinois, have invented and produced a new and original Design for Toys, of which the following is a specification, reference being had to the accompanying drawing, which is made a part hereof, and in which the figure is a perspective view of a toy embodying the design.

The invention consists in the features of novelty that are particularly pointed out in the claim hereinafter.

The new design comprises the parts B B, the part A, and one or more figures C C. The parts B B, when viewed in elevation, appear to be of semicircular shape, and when viewed from above appear to be of the shape of the letter U. The part A is cylindrical and ex-

tends from one of the parts B to the other. The figures C are situated between the parts B B, and are so outlined as to present the appearance of acrobats in the act of turning "hand-springs."

What I claim is—

The design for toys comprising the parts B B, which, when viewed in elevation, appear to be semicircular, the cylindrical part A, extending from one of the parts B to the other, and the figure C, situated between the parts B B and so outlined and marked as to present the appearance of an acrobat turning a hand-spring, substantially as shown and described.

THOMAS WHITNEY.
